UNITED STATES PATENT OFFICE

2,635,151

ELECTRIC SWITCH OR SWITCH-FUSE UNIT

William Sharp, Kings Norton, Birmingham,
EnglandApplication August 31, 1950, Serial No. 182,547
In Great Britain September 2, 1949

2 Claims. (Cl. 200—50)

1

This invention relates to electric switches having movable contacts in the form of cartridge fuses and it has for its object the provision of a new or improved switch or switch-fuse unit which is simple in construction, inexpensive to manufacture, and efficient in operation. A further object is to enable the entire set of fuse cartridges of the switch to be removed for inspection and replacement. A still further object is to mount and support the fuse cartridges so that the end caps will not be broken away from a glass tube forming the body of the cartridge. Further objects of the invention are to minimise arcing between the fixed and moving contacts of the switch or switch-fuse unit and to ensure that the faces of the said contacts are self-cleaning.

Referring to the drawings:

Figure 1 is a sectional plan view of a switch constructed according to this invention, the section being taken on line I—I of Figure 2.

Figure 2 is a section on line II—II of Figure 1 looking in the direction of the arrow.

Figure 3 is a section on line III—III of Figure 1 looking in the direction of the arrow.

Figure 4 is an end view of the switch casing showing the switch lever removed.

Figure 5 is an inside face view of the switch lever.

Figure 6 is an inside face view of a clamping bar of the moving contact carrier, and

Figure 7 is a face view of a socket or cap holding fuse carrier bars.

According to a convenient embodiment of this invention, the switch comprises a switch box 1 and the fixed contacts 2 to be bridged by the cartridge fuses 3 are mounted on electric insulating bars 4 fixed to the bottom of the box. The fixed contacts 2 comprise L-shaped copper strips, one arm of which is fixed to the insulating bar, whilst the other arm has a substantially trough or triangular shaped contact tip 5a, the contact tips being thus spring supported as the contact strips form spring arms. In this particular embodiment, three fixed contacts are fixed on one insulating bar 4, and three oppositely arranged contacts are fixed on the other insulating bar 4. The electric wires of each electric circuit are connected to opposite fixed contacts and until such pair of contacts are bridged the circuit is broken. The center portion of the movable contact carrier A comprises two half portions or bars 5 which have transversely arranged trough-shaped grooves 6a for receiving bridging contacts in the form of cartridge fuses 3. The cartridge fuses are of the usual construction com-

2

prising metal caps mounted on a cylinder of glass and connected by a fusible electrical conducting wire. The trough-shaped grooves are enlarged at each outer end for receiving the cartridge fuse caps to form shoulders for engaging the inner edge of each fuse cap, thereby locating the cartridge fuse centrally of the bars with a portion of a fuse cap projecting from each opposite face of the carrier A. Thus only the correct cartridge 10 fuse 3 can be fitted in the carrier. The two bars 5 are detachably held in the position clamping the fuses 3 by means of end caps or sockets, one cap 6 having a trunnion pin 8 projecting therefrom for engaging a hole in a flange of the switch cover 9. The said caps or sockets are made from a sheet metal plate on which the trunnion pins 8 and 18 respectively are fixed and the walls of the sockets are formed by bending up flanges 6a from the said metal plate, the flanges 6a being free to fit in the bars 5. The other end cap 7 is permanently mounted in the boss 7a on the opposite flange 10 of the cover, and the carrier parts are held together and in position on the cover by means of a helical spring 11 on the trunnion of the sliding carrier cap 6, which spring is compressed between such cap 6 and the inner face of the flange of the cover. The carrier caps 6 and 7 are conveniently oblong and the carrier A correspondingly shaped so that the carrier will always be replaced in the correct position. The carrier is given a snap-action control conveniently by means of a pin 12 rotatably mounted on a bracket 15 on the permanently mounted cover cap 7 and passing through a hole in a bracket 13 fixed to the cover, a helical spring 14 being mounted on the pin and being located between the bracket and the pivoted end of the pin. The bracket 15 limits the movement of the carrier in one direction by moving against a pin 17, whilst the movement in the other direction is limited by the bracket 15 moving against a pin 16, the pins 13 and 17 being on the cover 9. The dead centre position of the snap-action control may be arranged to give either a quick make and break or a slow break. The spindle or trunnion pin 18 on the permanently mounted carrier cap is fitted with an operating lever 19 having a notch 20 which engages a cross pin 21 on the trunnion pin 18 to provide for the required lost motion in the make or break. The switch lever is adapted 40 to engage a projection 22 on the box so that when the switch is in the "on" position, the switch cover is locked in position, and when the switch is in the "off" position the cover is free to be removed. For this purpose a tail piece on the lever 50 is provided with a circular flange 23 which en-

gages the pin 22 on the box when the switch is in the "on" position, but moves out of engagement with the projection when the switch is "off."

When the cover is placed in position the fuse cartridges are arranged at right angles to the bridging position, and when the switch is moved into the "on" position the projecting cartridge caps wipe over the spring supported fixed contacts and bridge opposite the fixed contacts. The movable bridging contact is an ordinary cartridge fuse and can be readily replaced as it is only necessary to remove the cover and detach the carrier. The carrier engages the cartridge fuse caps so that the cartridge fuses are not likely to be mechanically damaged. The bridge contact for the neutral may be a solid bar.

Having thus described the invention, what is claimed as new and desired to be secured by Letters Patent is:

1. An electric switch comprising a box for enclosing contact members of the switch, fixed contact members each comprising a spring blade mounted in the box on opposite sides thereof, contacts in the form of cartridge fuses having end caps for bridging said fixed contact members, a displaceable lid for the box, a carrier for said bridging contacts rotatably and detachably mounted in the said lid and located between said fixed contacts when the lid is on the box and adapted to move the bridging contacts into or out of bridging position, and comprising a centre portion divided longitudinally into two half portions, grooves in each longitudinal half with the grooves in one half portion registering with the grooves in the other half portion to clamp the caps of said cartridge fuses therebetween, socket members having trunnions rotatably mounted on opposite sides of said lid for detachably receiving and fixing together the said parts of the centre portion of the carrier, a lever mounted on one of said trunnion pins on a said socket member for moving said carrier into position bridging the fixed contacts or out of such position, and means on the box interlocking the said lever when the switch contacts are "closed" to prevent the dis-

placement of the lid until the switch contacts are "open."

2. An electric switch comprising a box for enclosing contact members of the switch, fixed contact members each comprising a spring blade mounted in the box on opposite sides thereof, bridging contacts in the form of cartridge fuses having end caps, triangular shaped tips on said spring blades for pressing on the end faces of the caps of the cartridge fuses, a displaceable lid for the box, a carrier for said bridging contacts rotatably and detachably mounted in the said lid and located between said fixed contacts when the lid is on the box and comprising a centre portion divided longitudinally into two half portions, grooves in each longitudinal half with the grooves in one half portion registering with the grooves in the other half portion to clamp said caps of the cartridge fuses therebetween, a socket member having a trunnion pin rotatably mounted on one side of the lid and adapted to receive said parts of the centre portion of the carrier to hold such parts together at one end, a socket member having a trunnion pin rotatably and slidably mounted on the opposite side of said lid and engaged on the other end of said centre portions of the carrier by sliding the socket on said trunnion pin, a lever mounted on the pin on the first mentioned socket member for moving the same into position, and means on the box interlocking with said lever when the switch contacts are "closed" to prevent the displacement of the lid until the switch contacts are "open."

WILLIAM SHARP.
